ATTORNEY

UNITED STATES PATENT OFFICE.

GILBERT THOMPSON, OF WASHINGTON, DISTRICT OF COLUMBIA, ASSIGNOR
TO J. C. LANG, OF SAME PLACE.

BILL-FILE.

SPECIFICATION forming part of Letters Patent No. 235,894, dated December 14, 1880.

Application filed November 3, 1879.

To all whom it may concern:

Be it known that I, GILBERT THOMPSON, of Washington city, in the county of Washington and District of Columbia, have invented certain new and useful Improvements in Paper-File Holders; and I do hereby declare the following to be a full, clear, and exact description of the invention, such as will enable others skilled in the art to which it appertains

10 to make and use the same, reference being had to the accompanying drawings, and to letters of reference marked thereon, which form a part of this specification.

Figure 1 is a front view of my improved 15 paper-file holder. Fig. 2 is a longitudinal sectional elevation taken in the plane $x-x$ of Fig. 1. Fig. 3 is a longitudinal sectional elevation, showing the file-holder proper suspended in position for examining the files. Fig. 4 is a plan 20 view of file-holder detached from box, and Fig. 5 is a perspective view of spring-catch detached from the file-holder.

Like letters in all the figures of the drawings indicate like parts.

25 This invention relates to a sheet-metal box or case for inclosing the file-holder, for keeping the files or papers free from dust and from being injured by vermin or water, and constructed so that the file-holder can be readily 30 suspended in position for a convenient examination of the files, and automatically locked in the box by means of a spring-catch, to allow of the box being pitched from a window in case of a fire without injuring or losing the 35 files from the box, as will be hereinafter more fully explained.

A represents the box, and B the file-holder, both of sheet metal, the latter having triangular sides, as seen in Figs. 2 and 3.

40 A sheet-metal plate formed with a spring-catch, a, at one end and a hook or flange, b, at the other is attached to the bottom or under side of the file-holder. The spring-catch is bent around the bottom front corner of the 45 file-holder and extends upward for a suitable distance, and has a ring, c, or its equivalent, attached to it for pulling the file-holder out of the box. To secure a proper working of the 50 spring-catch a strap, d, of sheet metal, is placed across it and attached to the front of the file-holder on each side of the spring-catch.

A wire holder, e, is attached transversely to the sides of the box, just up enough from the front bottom edge of the box for the spring-catch to impinge or catch against and hold 55 the file-holder in the box, the raising of the spring-catch up by the ring releasing it, so that the file-holder can be readily pulled out of the box.

C is a spring-clamp for clamping or keeping 60 the files closely together against the back of the file-holder; and it consists of a sheet-metal plate having a sufficient portion of it, D, bent up at a suitable angle from its bottom end to give the required spring, (see Figs. 2 and 3,) 65 and attached to a wire brace, E, bent to form an arm, f, at right angles on each side of the clamp, each end of the arm terminating in a hook, g, so that, by means of flanged strips or cleats F, attached to the sides of the file- 70 holder, the strips being provided with perforations h at proper and equal distances apart, the clamp can be readily adjusted to secure the papers by placing the hooks g of the arms in the proper holes. 75

The clamp may be inclined and held to support the papers in that position, (see Fig. 3,) so that they can be more conveniently handled and examined in the file-holder, by means of a piece of string, i, tied transversely to the end 80 perforations in the flanged strips, the clamp resting against the string, which will also prevent the clamp from falling out of the file-holder.

Flanged strips H H are attached to the front 85 of the file-holder for holding a label which is inserted between the strips.

It will be seen by inclosing the file-holder in a sheet-metal box or case, in the manner described, the papers will be kept perfectly free 90 from dust and from being injured by vermin, or water in case of a fire, the spring-plate on the bottom of the file-holder elevating it enough from the bottom of the box so that the water could not well reach the papers if it should get 95 into the box.

Boxes thus constructed can be arranged in tiers immediately one above the other to dispense with a good deal of shelving and casing, and the papers can be conveniently examined 100 without removing the file-holder to a table for that purpose, the file-holder being held in a

suspended position from the box by pulling the spring-catch *a* up by the ring *c* until it clears the wire holder *e*, and withdrawing the file-holder sufficiently to permit it to be tilted 5 or swung down for the flange *b* to catch onto the wire holder *e*, (see Fig. 3,) the lower corner end of the file-holder resting against the box immediately below. By slipping the hooks *g g* out of their respective holes in the flanged strips *F*, and moving the clamp *C* back, the papers are ready for examination.

A file-holder constructed with mechanism requiring some manipulation to fasten it after it had been put back into the box would be liable to be left unfastened, as but few persons would think of it at the time. Consequently in case of a fire, and where the box or boxes would, perhaps, be violently thrown around or out of a window on such an occasion, the 15 file-holders of those left unfastened would come out of the boxes and the papers thus be injured or destroyed.

An important feature of this invention is the automatic mechanism for avoiding this difficulty, the file-holder being automatically locked or fastened by the spring-catch the moment it is shoved into the box.

Another feature is, the file-holder is held in a suspended position from the bottom edge of 25 the box, thus facilitating the handling of the file-holder for examining the files and permitting one box to be placed immediately above the other.

Having thus fully described my invention, what I claim therein as new, and desire to secure by Letters Patent, is—

1. A paper-file holder consisting of a box, *A*, inclosing an inner case, *B*, to receive and hold the files or papers, provided with a spring-catch and a wire holder, *e*, combined and 40 adapted with box *A* and case *B*, substantially as and for the purposes set forth.

2. The sheet-metal plate formed with a spring-catch, *a*, at one end and a flange, *b*, at the other, and attached to the bottom of case 45 *B*, and arranged to automatically fasten it in box *A* by means of wire holder *e*, substantially as and for the purposes set forth.

3. The inner case *B*, having the spring-catch provided with a flange, *b*, arranged to suspend 50 the case from the front edge of box or case *A*, substantially as and for the purposes set forth.

4. The spring-clamp *O D*, having arms *ff*, with hooks *g g* on their ends, in combination 55 with perforated flanged strips *F*, attached to the sides of case *B*, substantially as and for the purposes set forth.

In testimony that I claim the foregoing I have hereunto set my hand this 25th day of 60 October, 1879.

GILBERT THOMPSON.
